MATERIAL REMOVER

George A. Lang, Cicero, Ill.

Application July 5, 1932, Serial No. 620,824

14 Claims. (CL 37—9)

This invention relates to material removers or excavators, and more particularly to a squirrel cage type shovel or snow excavator.

An object of this invention is to provide a new and improved material excavator.

A further object is to provide a snow excavator which will compact the snow during removal from the street or other surface and thus reduce its volume.

10 A still further object is to provide a snow excavator which is efficient and economical in operation.

Other objects and advantages of the invention will appear as the description proceeds.

15 A complete understanding of the invention may be had by reference to the following description taken in conjunction with the accompanying drawings, in which.

Fig. 1 is a fragmentary side view, partly in section, illustrating one embodiment of the invention;

20 Fig. 2 is a fragmentary rear view, partly in section, of the excavator apparatus shown in Fig. 1;

25 Fig. 3 is a fragmentary vertical sectional view of an elevator attachment for excavated snow shown secured to the left side of the apparatus, as viewed in Fig. 2;

30 Fig. 4 is a sectional plan view, on an enlarged scale, taken on the line 4—4 of Fig. 3;

Fig. 5 is a sectional plan view taken on the line 5—5 of Fig. 3;

35 Fig. 6 is a fragmentary side view, partly in section, of a modified form of the invention wherein means is included for melting the excavated snow, and

Fig. 7 is a vertical sectional view, on a reduced scale, taken on the line 7—7 of Fig. 6.

Referring now more in detail to the drawings, 40 wherein the excavator is shown as applied to the handling of snow, the excavator apparatus is mounted on a rectangular frame or chassis 11 built of structural channel members and at the rear end of the frame (Figs. 1, 2 and 7) are three 45 downwardly extending supports 12, to which is suitably secured an axle 14 on which a wheel 15 is rotatably mounted at each end. Each of the side channels of the frame 11 has mounted on its upper surface a support 16 to which are secured opposite ends of a fixed axle 17. The axle 17 supports a plurality of radially extending arms 18 (Fig. 1) which are arranged along and below the longitudinal center line of the excavator. The arms 18 are disposed at each side of the apparatus, and at a point intermediate the sides

two groups of arms are arranged adjacent each other (Fig. 2). Other arms 19 similarly spaced along the axle 17 of the apparatus as the arms 18 extend vertically from the axle 17 to provide a suitable unobstructed passage 20 (Figs. 1 and 2) extending transversely of the apparatus, the purpose of which will be described hereinafter. The arms 18 and 19 of each group support at their outer ends curved channels 23 providing continuous ring like or annular members surrounding the axle 17, except for the space between the opposed inner surfaces of the vertical arms 19 to provide the passage 20. Journalled on the ring like members formed from the curved channels 23 are a plurality of rollers 24 (Figs. 1 and 2), the rollers being aligned with each of the arms 18 and 19.

A rotary excavating wheel or shovel 25 of a squirrel cage type surrounds the rollers 24 and consists of two similar sections for the purpose 20 of allowing the apparatus to turn corners more readily. Inasmuch as the two sections of the rotary excavating shovel 25 are similar, but one of them will be described, the same reference characters, however, being applied to the respective parts of both. Each cage section of the shovel 25 has peripheral side flanges 26 (Fig. 2) provided with channels 27 on their inner peripheries in which the rollers 24 engage and ride to permit free rotation of the cages. Between the side flanges 26 of the cages and slightly within their outer peripheries are a plurality of similarly spaced excavator or pick up blades 30 built of two sections, which are plane surfaces, except for a groove or depression 31 extending longitudinally thereof. Intermediate the side flanges 26 of each cage is a stiffening ring 32 to which the two sections of the blades 30 extending therebetween are secured. The purpose of the depression 31 will be made apparent hereinafter. 40 These pick up blades 30 are narrower than the side flanges 26 leaving a space within the blades for the collection of snow. The inner limit of this space for collecting the snow is substantially defined by the outer periphery of a drum or cylinder 33 formed of a sheet of metal suitably secured to the outer peripheries of the annular channels 23. The cylinder 33 is open at the top (Fig. 1), across the transverse passage 20, for receiving the snow as will be more fully described 45 hereinafter.

As the squirrel cage rolls over the ground the weight of the apparatus presses the blades 30 through the snow and causes the snow to enter the space between the blades and the outer pe- 55

riphery of the cylinder 33. In order to compress the snow, compressor aprons 34 are hinged to the cylinder 33 along a line 35 (Fig. 1), one apron for each cage. The aprons 34 are forced downwardly by a plurality of rollers 37 carried by arms 38 extending through apertures 39 in the cylinder 33. The arms 38 are secured to rods 40 which are threaded at their lower ends and their upper ends are slidably mounted in downwardly extending sleeves 41 attached to the fixed axle 17. Threaded collars 44 having handles 45 are mounted on the lower threaded ends of the rods 40 and helical springs 46 are interposed between the sleeves and collars. Thus by rotating the handles 44 the downward pressure on the rollers 37 may be adjusted to vary the force of the springs 46 against the aprons 34 thereby providing means for compressing the snow as it passes the aprons between the blades 30 and the cylinder 33 under varying degrees of pressure in accordance with the thickness of the layer of snow to be picked up. In order to prevent the aprons 34 from coming in contact with the blades 30 of the cages the free ends of the aprons are bent upwardly and rearwardly as shown at 47. This bent portion 47 extends through a longitudinal slot in the cylinder 33 and in its lowermost normal position the rearwardly bent portion lies against the inner wall of the cylinder. It will be noted that the snow or other compressible material during its excavation, will first be compressed as it enters between the blades 30 in the movement of the excavator and will be further compressed by the compressor aprons 34 as it enters the space between the blades and the cylinder 33. Thus as the compressed material, entering the latter space, which material is a major portion of the excavated material, is carried upwardly between the blades 30 and the outer periphery of the cylinder 33, it is spaced from the cylinder, the material in this space being carried upwardly by its adhesion to the material locked between the blades.

For the purpose of assisting the pickup blades 30 to retain the snow compressed into an adhesive mass during the movement of the blades upwardly, at the rear of apparatus, there is provided a curved and tapered plowshare like member 48 fixed to rods 51 and an arcuate section 52 (Fig. 1) which is suitably spaced from the outer peripheral edges of the blades 30. The lower tapered end of the plowshare 48 is disposed close to the ground while the upper edge of the arcuate section 52 extends to the height of the axle 17. This arcuate section 52 is supported on the rear end of the frame 11 by three pairs of forwardly extending arms 53 (Figs. 1, 2 and 7) each pair comprising lower and upper arms which are secured to ribs 54 positioned directly behind the supports 12 as viewed in Figs. 2 and 7, the ribs being secured to the arcuate section 52. Secured to and extending between the lower ends of the ribs 54 is an angle iron 55 provided with apertures through which the rods 51 carrying the plowshare 48 extend. These rods 51 continue upwardly and rearwardly and pass through apertures in lateral extending plates 58 (Figs. 1 and 2) secured to the lower arms 53. Surrounding the rods 51 are helical springs 59 which abut against the lateral plates 58 at one end while the other ends of the springs abut against collars 60 secured to the rods 51 so as to hold the share 48 resiliently in place. The arcuate section 52 is further reinforced by ribs 61 at each end (Figs. 2 and 7).

The snow travels upwardly between the blades 30 of the squirrel cages and the inner cylinder 33 and is held in this space by the curved plowshare 48 and the arcuate section 52 during a portion of its travel. When the snow reaches the transversely extending passage 20 on the upper portion of the inner cylinder 33 it falls by gravity into the space within this cylinder. If the snow should tend to adhere to the lower edges of the blades 30 a scraper 62 (Fig. 1) provided on the forward side of the passage 20 positively directs the snow into the cylinder 33. The purpose of resiliently mounting the curved plowshare 48 is to permit it to yield in case the lower edge thereof comes into contact with an obstruction, such as a manhole cover, in the street or road. It will be apparent that the longitudinal grooves 31 in the blades 30 will also serve to retain the snow picked up by the blades in the pockets formed between adjacent blades, the grooves forming locking ribs in the snow pressed into the space between the blades.

Within the cylinder 33 is an endless conveyor, indicated generally by the numeral 64, for carrying the snow laterally from the cylinder to either side thereof. The sides of the conveyor 64 are enclosed by two vertical plates 65, the ends of which extend laterally beyond the sides of the excavating shovel 25 and are provided with journals for rotatably supporting shafts 66 and 67, a pair of which are at each side of the apparatus. The shaft 66 at the left side of the apparatus, as viewed in Fig. 2, extends rearwardly and is driven by a suitable motor indicated in dotted outline at 68 which is connected to the shaft by gearing indicated by the numeral 69. The motor 68 includes a reversing mechanism for driving the conveyor 64 in either direction, the motor being mounted on the rear end of the frame 11. Details of the motor 68 and the reversing mechanism have been omitted from the drawings, since they form no part of this invention and are not necessary to an understanding thereof. This last mentioned shaft 66 has a pair of gears 70—70 secured thereto which mesh with a pair of gears 71—71 secured to the shaft 67 for driving this shaft. This driven shaft 67 has secured thereto a pair of sprocket wheels 72—72 around which endless conveyor chains 73 pass to similar sprocket wheels on the other side of the apparatus. Extending between and secured to the inner sides of the conveyor chains 73 is a flexible floor 74 for the conveyor provided with a plurality of spaced blades. In order to assist the conveyor chains 73 and the attached floor 74 to support the weight of the snow a plurality of rollers 75 are rotatably supported under the conveyor floor 74. These rollers 75 are journaled in angle members 76 which are supported on channel members 77 supported between the vertical arms 19 at opposite sides of the passage 20.

A chute 78 is removably and adjustably positioned at each end of the conveyor 64 outside the sides of the shovel so that the snow delivered by the conveyor 64 may be discharged to either side of the road as circumstances may require and to various distances from the sides of the shovel. The side walls of the chutes 78 are provided with bifurcated portions 79 (Fig. 2) which straddle the shafts 67 at a point just outside the plates 65 thus permitting the chutes to be readily removed or placed in operative position as desired. For holding the chutes 78 in a desired adjusted position the plates 65 are provided with a series of apertures 80 arranged on a line concentric with 75

the axis of the shafts through which extend bolts 81 mounted in apertures in the side walls of the chute.

In cases where the snow is too heavy to be completely removed by a single passage of the excavator apparatus a suitable deflector or plow 83 may be attached to the front of the frame 11 to move a portion of the snow before the excavating shovel 25 passes thereover. The plow 83 is adjustably secured to the frame 11 by bolts 84 so that it may be raised or lowered in accordance with the depth of the snow.

A suitable eye or hook 85 is secured to the forward end of the frame 11 (Fig. 1) for coupling the excavator apparatus to a tractor or other pulling means for drawing the apparatus along the ground.

In cases where it is necessary to deposit the excavated snow, conveyed to either side of the apparatus by the conveyor 64, into trucks traveling alongside the apparatus, an elevator 87 (Fig. 3) may be attached to the particular side of the apparatus. The elevator 87 is designed to be removably attached to the two vertical side plates 65 of the conveyor 64 by means of substantially the same type as that described hereinbefore to secure the removable and adjustable chutes 78 to the plates, the chute being removed when the elevator is to be attached. The elevator attachment 87 comprises a housing 88 with an angularly disposed spout or chute portion 89 at its upper end. The side walls of the elevator attachment, which are attached to the conveyor side plates 65, are horizontally slotted for receiving the shafts 66 and 67 when securing the same to the side plates. The mentioned side walls of the attachment are provided with journals for rotatably supporting shafts 92, 93 and 94. Secured to the shaft 92 at each end thereof outside the side walls of the attachment are gears 95 which mesh with aligned gears 96 (Figs. 3 and 5) secured to opposite ends of the shaft 67 of the conveyor 64. The gears 95 mesh with gears 99 aligned therewith and secured to the shaft 93. Fixed to each of the shafts 93 and 94 is a pair of sprocket wheels 100 and 101 around which endless conveyor chains 102 pass. Pivotally secured to the inner sides of the conveyor chains 102 are a plurality of rectangular shaped blades 103 (Figs. 4 and 5) which have operatively connected thereto at each end a pair of guide rollers 104 engaging in guide channels 107 suitably arranged on the walls of the housing 88 and on a wall 108 dividing the housing into two compartments, one for the loaded vertically moving blades 103 and another for the blades after they have deposited their load into the chute portion 89 and are moving downwardly. The wall 108 primarily serves to retain the snow deposited on the blades 103 during their upward movement. In the operation of the excavator apparatus and with the elevator 87 attached to the left side of the apparatus (Figs. 2 and 3) and with the horizontal conveyor 64 traveling in the direction indicated by the arrow it will be apparent through the train of gears 96, 95 and 99, the gears 96 receiving motion from the shaft 67, that the right hand portions of the elevator conveyor chains 102 will travel upwardly and consequently the snow deposited on the attached blades 103 from the horizontal conveyor 64 will be deposited in the chute 89 and fall therefrom by gravity into the truck traveling with the excavator apparatus. The operation of the elevator 87 when attached to the right side of the apparatus after the reversing

mechanism (not shown) has been operated to cause the horizontal conveyor 64 to travel toward the right side of the apparatus is accomplished in the same manner as that described above in connection with the elevator when attached to the left side of the apparatus.

Suitably supported upon the frame 11 and disposed above and adjacent the periphery of the wheel or shovel 25 and extending entirely across the width of the shovel is a header 110 from which project a plurality of nozzles 111 (Figs. 1 and 2). The header is connected to a plurality of pipes 112 which are connected to a suitable source of fluid under pressure such as air or water (not shown), which may be carried on the frame 11 of the apparatus. The purpose of the nozzles from which jets of fluid under pressure may be emitted, as desired, is to blow from the shovel 25 the snow locked in the pockets formed between the pick-up blades 30 as they pass the nozzles onto the conveyor 64, the blown snow passing through an opening 113 formed in the scraper 62. This serves to clean the blades 30 of snow and thereby provides increased capacity for picking up snow of a greater depth from the ground, thus increasing the efficiency of the apparatus. If the layer of snow on the ground is not very deep the operation of the jets from the nozzles 111 can be dispensed with and the snow permitted to remain locked between the pickup blades 30 and subsequently be pushed into the space between the blades and the outer periphery of the cylinder 33 at the point where the shovel 25 passes over the snow on the ground.

In a modified form (Figs. 6 and 7) of the excavator apparatus of this invention, hereinbefore described, an oven 116 is installed in the passage 20 above the axle 17 and between the vertical arms 19. The oven 116 is provided with side and end walls and an upper curved wall, just inside the inner edges of the pickup blades 30, which include a thickness of refractory material, the walls being built around the side flanges 26 and the channels 27 of the rotatable squirrel cages of the shovel 25. The upper right hand corner of the oven 116 (Fig. 6) is provided with an opening 117 for receiving the excavated snow which falls by gravity from the blades 30, as the blades carry the snow past the opening in the top portion of the inner cylinder 33, into the oven. An outer edge of the upper curved wall of the oven 116 at the upper end of the opening 117 serves to scrape from the blades 30 any snow adhering to the lower edges of the blades as they travel past the opening. The snow as it falls into the oven 116 is melted by jets of flame, from gas or oil burners 118, directed into the oven from opposite ends thereof, three burners being arranged at each end. The burners 118 may be supplied with gas or oil from a suitable supply source mounted on the frame 11 of the apparatus. An inverted V-shaped grille plate 119 is disposed between the jets of flame from the two pairs of upper burners 118 and the two lower burners for receiving the snow which is not melted in passing the jets of flame, the snow so received then being melted by the jets of flames from the lower burners. The water from the melted snow passes through a sieve 120 and into a catch basin 121 at the bottom of the oven structure. Opposite ends of the catch basin 121, which are disposed at the sides of the excavator apparatus, have connected thereto interconnected similar drain pipes 122 and a removable spout 123 so that the water from the catch basin may be directed to the ground direct-

ly adjacent the line of travel of the excavator apparatus or by means of the spout directed to either side of the road as desired.

5 A means substantially similar to that hereinbefore described for blowing the snow locked between the pickup blades 30 at the top of the shovel 25 may be used in connection with the last described type of excavator which includes the oven 116. Referring to Figs. 6 and 7, an opening 10 124 is provided in the upper wall of the oven 116 for the passage of the snow blown from the nozzles 111 disposed adjacent the periphery of the shovel 25.

15 As the apparatus is drawn along the ground the squirrel cages of the shovel 25 roll freely and independently of each other on the rollers 24 carried by the arms 18 and 19 secured to the fixed axle 17 and in the manner hereinbefore described the snow is excavated from the layer 20 thereof on the ground or road and deposited at either side of the road or line of travel of the apparatus or into a truck traveling alongside the apparatus in one embodiment of the apparatus or melted and drained to either side of the road 25 in the second embodiment of the apparatus.

30 Although the invention as herein illustrated and described is particularly well adapted for use in connection with the removal of snow from the street or other surface and depositing it at various distances from the line of travel of the apparatus or in trucks traveling alongside thereof, it should be understood that the novel features thereof are capable of handling other materials than snow and should be limited only by the scope of the appended claims.

35 What I claim as new and desire to secure by United States Letters Patent is:—

1. In a movable excavator, an excavator wheel 40 having a plurality of excavator blades fixed relative to said wheel, a drum within said blades and forming an annular space between the blades and the drum for receiving material moved radially thereto from between said blades, means for mounting said wheel for rotation to convey material in said space, and means for causing said materials to be discharged into said drum.

50 2. An apparatus of the class described comprising a stationary drum, an excavator wheel disposed concentrically about said drum and leaving a space around said drum for receiving material, said wheel having radial flanges, blades disposed transversely between said flanges for excavating material, and means disposed at the rear side of said wheel for retaining the excavated material on the wheel as it moves upwardly.

55 3. An apparatus of the class described comprising a stationary drum, open at the top, an excavator wheel rotatably disposed about said drum and leaving a space around the drum, means for compressing the material being excavated in said space, and means for discharging said material into the open top of the drum.

60 4. An apparatus of the class described comprising a fixed axle, annular members extending about said axle, a plurality of arms interconnecting said annular members with the axle, a drum secured to said annular members and being open at the top, a plurality of rollers carried by said annular members and extending 65 through said drum, and an excavator wheel rotatably mounted on said rollers for elevating materials and discharging them into the drum.

70 5. An apparatus of the class described comprising a rotatable excavator wheel having a plurality of excavator blades fixed relative to said

wheel, said wheel being rotated solely by the movement of the apparatus, an endless conveyor movable laterally and disposed within said wheel, a pair of walls adjacent said conveyor forming a conveyor channel, means for driving said conveyor, and means for directing materials from said wheel into said channel onto said conveyor.

5 6. An apparatus of the class described comprising a drum, an excavator wheel rotatable about the drum and having blades spaced from the drum to provide a free space for receiving materials, a compressor for the materials in said space, and means for adjusting the pressure exerted by the compressor.

10 7. An apparatus of the class described comprising a drum, an excavator wheel having a plurality of excavator blades fixed relative to said wheel, said wheel being rotatable about said drum solely by the movement of the apparatus, a pair of supports extending axially within the drum, a plurality of rollers journaled in said supports, and a conveyor movable over said rollers to convey materials delivered to the drum laterally from the drum.

15 8. In a movable excavator, an excavator element having a plurality of blades adapted to pick up and retain material therebetween during movement of the excavator element, means for compressing the material during its pickup, means within said blades, open at its top, for receiving material from between the blades, and means arranged outside of the excavator element for effecting the removal of the material from between the blades to cause it to move into the open top of the material receiving means.

20 9. In a movable excavator, an excavator wheel having a plurality of blades adapted to pick up and retain material therebetween during movement of the wheel, a drum within and spaced from said blades to provide an open space for receiving material, said drum being open at its top, for receiving material from between the blades and said space, and means for directing fluid under pressure against the material retained by the blades to cause it to move into the open top of the drum.

25 10. In a movable excavator, an excavator wheel having a plurality of excavator blades formed with longitudinally extending depressions for retaining material received between the blades during movement of the wheel.

30 11. In a movable excavator, an excavator wheel having a plurality of excavator blades, a drum having an opening for receiving material arranged within said blades and forming an annular space between the blades and the drum for receiving material moved radially thereto from between said blades, means for rotatably supporting said wheel about said drum, and stationary means within said space for causing said materials to be discharged therefrom into said drum.

35 12. An apparatus of the class described comprising a drum, an excavator member rotatable about the drum and having blades spaced from the drum to provide a free space for receiving materials, a yieldable element hinged to said drum for compressing the materials in said space, and means carried within said drum and operatively engaging said compressing element through an opening provided in said drum for adjusting the pressure exerted by the compressing element.

40 13. In a movable excavator, a movable excavator member having a plurality of material excavating elements, means spaced from said ele- 45

ments and forming a limited space within said elements for receiving material from between said elements, and means for compressing the said material in said space as it is received therein for causing the same to be carried upwardly in the movement of said excavator member by its adhesion to the material between said elements.

14. In a movable excavator, an excavator wheel

having a plurality of excavator blades spaced short distances apart, said blades alone being effective in the movement of the wheel to excavate material, said blades being formed with depressions effective for retaining material received between said blades during movement of the wheel.

GEORGE A. LANG.
